CARD SELECTING DEVICE

Lionel J. Gottschalk, New Orleans, La.

Application June 10, 1949, Serial No. 98,224

3 Claims. (Cl. 129—16.1)

1

My invention relates to card selecting devices. An object of this invention is to provide a device for separating selected cards from those rejected or non-selected by mechanical means through the use of magnetic attraction to which the cards respond.

Another object is to provide means by which the rejected cards may be separated from the selected cards and still be held in proper alphabetical or numerical arrangement with relation to the entire stack of cards while at the same time providing ready access to the selected cards in order that they may be consulted.

Another object is to accomplish the foregoing results by providing cards having properly placed holes, slots, and magnetically attractive metal clips, these clips being so positioned as to be contacted by the magnet of a magnet tipped slide bar.

Another object is to provide a filing tray for cards whereby the cards may be readily transferred while in the tray to the selecting device without removal from the tray.

The novel features which I believe to be characteristic of this invention are set forth particularly in the appended claims. The invention itself, however, both as to organization and operation, together with additional objects and advantages thereof, will be best understood from the following description of a specific embodiment when read in connection with the accompanying drawings in which,

Fig. 1 is a perspective view of the device having a small portion broken away.

Fig. 2 is a side elevational view on a reduced scale and showing a plurality of cards in the device some of which are being selected.

Fig. 3 is a front elevational view on an enlarged scale showing two of the cards, No. 1 of which has been selected.

Fig. 4 is a perspective view of a tray in which the cards may be kept and taken to the selecting device.

Specially designed cards are intimately involved in combination with the structural features of the device and will be described first with reference to Fig. 3 of the drawings. The cards which are designated in general by the numeral 5 are provided with centrally positioned slots 6 in their lower edges. At opposite sides of these slots, magnetic metal clips 7 and 8 are secured to the cards in suitable manner such as by stapling. Each card near one of its ends is provided with an upper hole 9 and lower hole 10 for a purpose which will appear later in the description as will also slots and other holes now to be mentioned. Each card near its upper edge is provided with a set of holes 11 and an opposite set designated 12. For illustrative purposes, each set is shown as having five holes. Asso-

2

ciated with the two sets of holes respectively shown in card No. 1, there are open ended slots 13 and 14, while in card No. 2, there are differently located slots 13' and 14'. It will be understood that these slots for cards bearing different information are differently located with relation to the sets of holes 11 and 12 respectively. Each card somewhat inwardly from an upper corner thereof is provided with a closed slot 15. A plurality of rods such as indicated by the letters RS are provided for variable insertion through the holes and slots.

The selecting device proper includes a base member 16, the upper side of which is provided with a longitudinal channel 17 for receiving a slide bar 18. A handle 19 is secured to the forward end of this bar while a permanent magnet is secured to its rear end. As shown in Fig. 1, this magnet consists of two inclined side members 20 connected by a cross member 21. The upper side of the bar 18 carries a rib 22 over which the slots 6 of the cards are adapted to fit and be kept in alignment upon the sliding bar 18 as will be understood from Fig. 2. Front and rear end members 23 and 24 extend upwardly from the base member 16. The lower portions of these end members as shown in Fig. 1 are cut away to slidably receive the bar 18 and its rib 22. One of the sides of the end members 23 and 24 is provided with corresponding slots 25 which curve upwardly to an open end. The other sides of these two members have their corners cut away arcuately as indicated at 26, and each is provided with a lower perforation 27. These two members near their upper edges are provided with sets of holes 11' and 12' corresponding to the holes 11 and 12 in the cards 5.

Fig. 4 shows a tray having end members 28 and 29 whose lower portions are cut away the same as the end members 23 and 24 of the device. The end members 28 and 29 of the tray at one side thereof are provided with elongated slots 30 and 31 while near the bottom of the opposite side, they are provided with holes 32 and 33. One of the sides of the tray is hinged as indicated at 34. It should be noted that the upper edges of the end members 28 and 29 are lower than those of the members 23 and 24 of the selecting device in order that the tray may be used to advantage with the selecting device proper as will be explained in connection with the manner of operating the device.

The operation and advantages of this invention will be apparent in connection with the foregoing description and the accompanying drawings. After the stack of cards to be selectively separated is placed between the end members 23 and 24 so as to rest upon the top surface of the slide bar 18 and astride the centering rib 22, two or more of the selecting rods RS are in-

serted through the proper holes in the end members 23 and 24 so as to extend through the proper holes and open ended slots in the stack of cards which are cooperatively related to the cards it is desired to select. Then the slide bar 18 having the inclined magnet 20-21 attached to its rear end is pulled forwardly. As this magnet successively comes into contact with the magnetic metal clips 7 and 8 secured to the bottom edges of the cards, those cards having the properly placed open ended slots 13 and 14 corresponding to the inserted rod or rods will be drawn downwardly so as to rest upon the base member 16 as shown in Fig. 2. The cards which are not to be selected will be held up by the rod or rods RS which were passed through one or more of the closed holes indicated at 11 and 12. Therefore these cards resist being attractively drawn down to the base member.

After the slide bar has been completely withdrawn, a rod is inserted through the holes 9 in non-selected cards so as to extend past the cut away end covers at 26; a rod passed through the holes 27 in the end members and through holes 10 in the selected or dropped cards; also a rod R preferably larger than the selector rods RS is passed through the open ended slots 25 in the end pieces and through the slots 15 in the cards. the selector rods are then withdrawn. The selected and lowered cards are held in place on the base member 16 by the rod which was passed through the holes 27 and 10, these cards of course being lower down than the rejected or non-selected cards. It is to be understood that the distance the holes 9 and 10 are from the adjacent edges of the cards is less than the distance the selected cards drop when the slide bar is removed. Then by means of the rod passing through the holes 9 of the rejected cards and through the cut out 26 of the end members, these rejected cards can be swung around the rod R as a pivot away from the selected cards which can then be gone through for desired information, after which the rejected cards can be quickly swung back into their original respective places in the stack as will be readily understood by referring to Fig. 3.

It will be understood that after the cards relating to a broad classification have been selected, it is possible to make further selections from such cards for sub-divisions coming under the broad classification.

While a stack of cards may be taken from an ordinary filing tray and placed in the selecting device, Fig. 4 shows a specially constructed tray which is adapted to be used in cooperation with the selecting device in such manner that the cards will remain in the tray when placed in the selecting device. In order to accomplish this result, the lower portion of the end members 28 and 29 are cut away the same as the end members 23 and 24 so as to straddle the sliding bar 18 and its rib 22. In the use of this tray, the rod R on account of passing through the slots 30 and 31 of the tray and the slots 15 of the cards, serves to keep the cards properly positioned in the tray. The side of the tray hinged at 34 permits the rejected cards to be readily swung upwardly and to be swung back into original position after the selected cards have been inspected.

It will be understood that the provision of two sets of holes 11 and 12 in the cards increases the number of selections that can be made and that by increasing the number of holes, a still greater number of selections is possible.

I claim:

1. In a card selecting device, the combination of a base member, two spaced apart end members extending upwardly from said base member, the lower portions of said end members being cut out, a bar slidably supported on said base member and adapted to slide lengthwise through said cut out portions, a downwardly inclined magnet secured to the rear end of said bar, a plurality of cards placeable between said end members for resting on said bar, magnetically attractive members secured to the bottoms of said cards and adapted to be successively contacted by said magnet to displace selected cards downwardly with relation to the other cards, and means associated with the latter cards whereby they resist such displacement.

2. In a card selecting device, the combination of a base member, two spaced apart end members extending upwardly from said base member, the lower portions of said end members being cut out, a bar supported by said base member for sliding lengthwise through said cut out portions, a downwardly inclined magnet carried by the rear end of said bar, a plurality of magnetically attractive cards placeable between said end members for resting on said bar for successive contact by said magnet as said bar is slid to displace selected ones of said cards downwardly with relation to the other ones of said cards, and means associated with the latter cards whereby they resist such displacement.

3. In a card selecting device, the combination of a base member, two spaced apart end members extending upwardly from said base member, the lower portions of said end members being cut out, a bar supported by said base member for sliding lengthwise through said cut out portions, a downwardly inclined magnet carried by the rear end of said bar, a plurality of magnetically attractive cards placeable between said end members for resting on said bar for successive contact by said magnet as said bar is slid to displace selected ones of said cards downwardly with relation to the other ones of said cards, means associated with the latter cards whereby they resist such displacement, each of said end members at one margin thereof containing a curved open ended slot, each of said cards at its margin corresponding to the aforesaid margin containing a closed slot, a pivot rod insertable through said open ended slots and through said closed slots upon which rod the non selected cards may be swung back and forth with relation to the selected cards, and means for retaining the selected cards in their said downward position.

LIONEL J. GOTTSCHALK.
